UNITED STATES PATENT OFFICE.

FRANK H. FRISSELL, OF MIDDLETOWN, CONNECTICUT, ASSIGNOR TO THE RUSSELL MFG. CO., OF MIDDLETOWN, CONNECTICUT, A CORPORATION.

BELTLIKE CARTRIDGE-CARRIER FOR MACHINE-GUNS.

1,168,876.

Specification of Letters Patent.

Patented Jan. 18, 1916.

Continuation in part of application Serial No. 20,816, filed April 12, 1915. This application filed August 10, 1915. Serial No. 44,795.

To all whom it may concern:

Be it known that I, FRANK H. FRISSELL, a citizen of the United States, residing at Middletown, in the county of Middlesex and

5 State of Connecticut, have invented a new and useful Improvement in Beltlike Cartridge-Carriers for Machine-Guns; and I do hereby declare the following, when taken in connection with the accompanying drawings 10 and the characters of reference marked thereon, to be a full, clear, and exact description of the same, and which said drawings constitute part of this application, and represent, in—

15 Figure 1 a plan view of a section of a machine-gun, belt-like cartridge-carrier made in accordance with my invention and shown as filled with cartridges. Fig. 2 an edge view thereof looking at the bullet ends 20 of the cartridges. Fig. 3 a diagrammatic view showing the principle on which my improved belt-like cartridge-carrier is woven, the warp threads being actually crossed at regularly spaced intervals determined in 25 length by the size of the cartridge-receiving pockets, and the weft threads being alternately interwoven with the warp threads as the same respectively appear upon the opposite sides of the belt-like fabric which is two- 30 fold or double in its character although integral in physical structure.

My invention relates to an improvement in woven, belt-like cartridge-carriers for machine-guns. As heretofore made, such carriers have consisted, in effect, of two independently woven strips of narrow fabric placed side by side, and, to use the weaver's term, "stitched" together at regular intervals for the production of cartridge-pockets 40 by the localized lateral interlacing of the warp and weft threads during the weaving of the strips face to face. Cartridge-carriers so made, have been found objectionable because, on account of the severity of their 45 usage in machine-guns, the "stitching" breaks down and permits the cartridges to run together and foul the mechanism of the gun which is thus put out of commission, and also because the production of the 50 cartridge-pockets by "stitching" does not permit of securing that degree of uniformity as to their size which is demanded for the best results with the belts in feeding the cartridges.

The object of my invention is to so reinforce the ends of the cartridge-pockets that it is impossible to break down the pockets without destroying the fabric, and to insure uniformity in the size of the pockets. 55

With these ends in view, my invention 60 consists, broadly, in a woven belt-like machine-gun cartridge-carrier having two sets of warp threads crossing each other at regularly spaced intervals so as to alternately appear upon the opposite sides of the fabric 65 and produce a series of cartridge-pockets reinforced by the crossing of the said warp threads, and one or more weft threads interwoven with the said warp threads.

My invention further consists in certain 70 details of construction as will be hereinafter described and pointed out in the claims.

According to my present view, the preferred way of carrying out my invention is to set up a suitable loom with two sets of 75 warp threads 2 and 3 and two weft threads 4 and 5. The mechanism of the loom is arranged so that at regularly spaced intervals the respective sets of warp threads will entirely cross each other and actually change 80 sides, as shown in Fig. 3, so as to appear and reappear upon the respective faces of the fabric. The weft threads 4 and 5 do not cross each other but are alternately interwoven with the alternating sections of the 85 warp threads as the same change sides by crossing at regular intervals. This results in the production of a belt-like fabric containing a longitudinal series of cartridge-receiving pockets 6 reinforced at their ends 90 and therefore between the adjacent cartridges 7, by the crossing of the warp threads in such a manner that the pockets cannot be broken down without destroying the fabric. Furthermore, the crossing of the warp 95 threads at regular intervals enables the cartridge-pockets to be produced with a far greater degree of accuracy than when the warp threads and weft threads are locally interlaced in the old way to form the cartridge-pockets. In other words, after a predetermined number of picks, the warp-threads are crossed so that the pockets are marked off, as it were, with absolute accuracy. 100

As herein shown, and preferably, the 105 outer edges of the strips of fabric are reinforced by special warp threads 8 of hard wound linen or cotton so as to increase the

hardness of the edges and endow them with a tendency to stand apart rather than hug each other, whereby the insertion of the cartridges into the pockets is facilitated.

The crux of my invention is the actual crossing of the warp threads at regularly spaced intervals so that they will alternately appear upon the opposite sides of the fabric, rather than in any particular mode of applying weft threads. Thus the loom might be set up by a weaver skilled in weaving such fabrics, so that a single weft thread might be interwoven with warp threads crossed in accordance with my invention; or again he might set up the loom to employ two weft threads without alternately interweaving them with the respective sets of warp threads.

This case is a continuation of my application filed April 12, 1915, Serial No. 20,816.

I claim—

1. As a new article of manufacture, a woven belt-like machine-gun cartridge-carrier having two sets of warp threads crossing each other at regularly spaced intervals so as to alternately appear upon the opposite sides of the fabric and produce a series of cartridge-pockets reinforced by the crossing of the said warp threads, and weft threads interwoven with the said warp threads.

2. As a new article of manufacture, a woven belt-like machine-gun cartridge-car-

rier having two sets of warp threads crossing each other at regularly spaced intervals so as to alternately appear upon opposite sides of the fabric and produce a series of cartridge-pockets reinforced by the crossing of the said warp threads, weft threads interwoven with the said warp threads, and supplemental warp threads reinforcing the edges of the fabric to stiffen them and prevent them from hugging together. 35 40

3. As a new article of manufacture, a woven belt-like machine-gun cartridge-carrier consisting of two sets of warp threads crossing each other at regularly spaced intervals so as to alternately appear upon the opposite sides of the fabric, and of weft threads alternately interwoven with the respective sets of warp threads but not changing 45 50 sides therewith.

4. As a new article of manufacture, a woven belt-like machine-gun cartridge-carrier consisting of two sets of warp threads crossing each other at regularly spaced intervals and thus alternately appearing upon opposite sides of the fabric, and of two weft threads alternately interwoven with the respective sets of warp threads but not changing sides therewith, the outer edges 55 60 of the fabric being stiffened by special warp threads to prevent them from hugging together.

FRANK H. FRISSELL.
